COMBINED INK-MARKING AND PERFORATING MACHINE

Arthur W. Altvater, University City, and Franz Wunder, Maplewood, Mo.; said Wunder assignor to said Altvater

Application April 16, 1937, Serial No. 137,256

8 Claims. (Cl. 101—316)

The present invention relates to shoe machines and more particularly to machines for performing combined ink-marking and perforating operations.

5 Cut-out machines, such as the well-known "Western", are used extensively in the shoe industry to perform perforating and cut-out operations in shoe uppers and various parts thereof. Ink-marking attachments have been used 10 also in connection with these well-known types of machines, which required special dies. This operation of combined ink-marking and perforating is performed also on a special machine which is used separately from the regular shoe 15 factory machines for performing perforating operations.

The principal object of the present invention is to produce an attachment for a regular shoe factory cut-out machine to adapt it to perform either a combined ink-marking and perforating operation or, through the removal of the inking means from the attachment, its regular 20 perforating operation.

To the accomplishment of this object, and 25 such others as may appear hereinafter, the various features of the present invention reside in certain devices, combinations and arrangements of parts hereinafter described and then set forth broadly and in detail in the appended 30 claims which possess advantages readily apparent to those skilled in the art.

The various features of the present invention will be readily understood from an inspection 35 of the accompanying drawings illustrating the best forms of the invention at present known to the inventors, in which,

Fig. 1 is a view in right side elevation, partly in section, of the "Western" cut-out machine;

40 Fig. 2 is a detail view in plan of the ink-marking and perforating attachment for the "Western" cut-out machine;

Fig. 3 is a detail view in right side elevation of the ink-marking and perforating attachment;

45 Fig. 4 is a detail view in sectional elevation on the line 4—4, Fig. 2;

Fig. 5 is a detail view in plan of another form of an ink-marking and perforating attachment for the "Western" cut-out machine;

50 Fig. 6 is a detail view in right side elevation of the attachment illustrated in Fig. 5;

Fig. 7 is a detail view in sectional elevation on the line 7—7, Fig. 5;

55 Fig. 8 is a detail view in front elevation of the combined ink-marking and perforating die used

in connection with the attachment illustrated in Figs. 1, 2, 3 and 4, and

Fig. 9 is a detail view in sectional elevation on the line 9—9, Fig. 5.

The illustrated embodiments of the present invention comprise attachments for the well-known "Western" cut-out machine illustrated generally in Fig. 1. As shown this machine comprises a bed 9, a pressing member 10, a face plate 11 thereon, and a paper-cutting bed 12 for 10 the face plate, generally in accordance with standard cut-out machine construction.

As usual in this type of machine the bed 9 supports a pair of rails 13, (only one of which is shown), extending forwardly beyond the bed. 15 Adjacent the front and back of the bed 9, these rails 13 are carried, respectively, by the arms of V-shaped supports 14 and 15 which are mounted upon a horizontal rod 16 carried by the bed 9, the construction being such as to permit the rails 13 to be moved on the surface of the bed 20 towards and from each other to accommodate between them dies of different widths.

The rails 13 form a guideway for the side edges of a plate 17, (Figs. 2 and 3), which rests 25 upon the upper surface of the bed 9. The plate 17 is provided with forward extensions 18 and 19, (Figs. 2, 3 and 8), which rest, respectively, upon the forward extensions of the rails 13. The plate 17 is clamped to the rails 13 by 30 clamps 20 and 21, (Figs. 3 and 8). Each clamp is provided with a horizontal portion 22 which engages the rail 13 and a vertical portion 23 which engages the inside edge of the plate extensions. The horizontal portion is received 35 loosely by a screw provided with a finger piece 24 and a shank 25 which is threaded into the plate extensions. The clamps 20 and 21 are spring clamps. To this end a spring 26 is coiled about the shank 25 and is interposed between 40 the horizontal portion 22 of the clamps and the bottoms of the plate extensions.

The plate 17 is provided with two rails 27 and 28, (Fig. 2), which embrace the sides of the combined ink-marking and perforating die 29 45 and guide it for sliding movement upon the plate 17 from a position of clearance, in which position an inked and perforated piece of work is removed from the die and a piece to be inked and perforated is located on the die, to 50 and from a position of pressure, in which position, (Figs. 1 and 2), the work is inked and perforated.

The die 29 comprises two sets of perforating tubes 30 and 31, (Fig. 2), associated, respec- 55

tively, with two sets of markers 32 and 33. The perforating tubes are mounted in a tube plate 34, (Fig. 4), which rests upon a tube plate 35. The plates 34 and 35 are mounted upon a bottom plate 36. The perforating tubes are hollow so that the pills perforated out of the work may pass therefrom into openings 37 formed in the tube rest plate 35, from which the pills drop upon the plate 17. To this end the bottom plate 36 is cut away, as indicated in Fig. 4. The pills which drop out of the openings 37 upon the plate 17 are wiped therefrom by the bottom plate 36 when the die is moved from the position of pressure to the position of clearance. The pills wiped from the plate 17 drop harmlessly through the space 38, (Figs. 2 and 3).

The markers 32 and 33 are formed by routing them out of a solid brass blank so that the marking edges 39, (Fig. 3), rise vertically from a flange 40, (Fig. 3), integral therewith. The flange 40 is supported upon the ends of studs 41 which pass loosely through the die plates, each stud 41 having a head 42 which works in an opening 43 in the plate 36 and engages the bottom of the tube rest plate 35. The marking edges 39 of the markers 32 and 33 are held normally elevated in a plane above and spaced from the plane of the cutting ends of the perforating tubes 30 and 31 by a spring 44 coiled about each stud 41 and interposed between the flange 40 and the tube holder plate 35.

The work during the ink-marking and perforating operation is supported upon a stripper plate 45, (Figs. 2 and 3), carried upon the upper end of studs 46 which pass loosely through the die holder and die rest plates, there being a head 47, on each stud, which works in an opening 48 formed in the tube rest and bottom plates, and engages the tube holder plate.

The stripper plate 45 is held normally in the position of Fig. 3 by a plurality of coiled springs 49, the bottom ends of which are seated, respectively, in seats 50 formed in the tube holder plate and the upper ends of which are engaged with the bottom of the stripper plate. The work-supporting surface of the stripper plate is provided with work-gauging pins 51 of the bumper type and with leaf spring work-clamping clips 52.

As indicated in Fig. 2 the stripper plate 45 is provided with apertures 53 and 54 conforming generally to the perforating tube and marking edge pattern. When the face plate 11, (Fig. 1), on the bottom of the platen 16 forces the backing paper 12 initially against the work, the springs 49 back up the stripper plate 45 with sufficient pressure to cause the work to be flattened thereon and to be drum-headed across the apertures 53 and 54. Then the stripper plate, the paper-backed face plate and the work clamped therebetween are carried down to engage the drum-headed portion of the work successively with the marking and perforating dies. After the ink-marking and perforating operation the work remains clamped between the stripper plate and the paper-backed face plate until the stripper plate returns to its original elevated position whereupon the ascending paper-backed face plate withdraws from the work and leaves it free to be withdrawn from beneath the spring clips 52 after the die has been pulled forward into the position of clearance.

The front face of the die bottom plate 36 is provided with a handle 55, (Figs. 2 and 3), which is grasped by the operative to slide the

die from the position of clearance to the position of pressure and then, after the ink-marking and perforating position, back to the position of clearance.

In order to ink the marking edges 39 each time the die is moved into the position of clearance from the position of pressure, the attachment is provided with an inking means which is first inserted between the marking edges 39 and the bottom of the stripper plate 45 and then the marking edges 39 are moved vertically to cause them to engage the inking means. With this construction all danger of depositing ink upon the work-supporting surface of the stripper plate 45 is obviated.

The inking means comprises an absorbent ink pad 56, (Fig. 4), which is secured to the bottom of a guard plate 57, the front and rear edges 58 and 59 of which are bent downwardly. The rear edges 59 are bent to insure the stripper plate 45 riding up over the top surface of the guard when the die is moved from the position of pressure into the position of clearance. The guard plate 57 is secured to a pair of arms 590 and 60, (Fig. 2), secured, respectively, to blocks 61 and 62 which are pivotally mounted upon brackets 63 and 64 secured, respectively, to the rails 18 and 19. To this end each bracket is provided with an opening 65 which receives loosely the shank of a screw 66 threaded into the guard plate arm-supporting block. The screw 66 is provided outside each bracket with a finger piece 67.

The guard plate 57 is provided with a plurality of openings 68, (Fig. 2), through which the ink pad 56 may be provided with ink. The guard plate 57 may, however, be swung about its pivotal connection from the full line position of Fig. 1 to the construction line position thereof in order to reverse the position of the ink pad and thus expose it to view to facilitate the application of ink thereto.

The ink pad 56 is locked in the position of Figs. 2 and 4 by clamps 69 and 70 pivoted, respectively, on vertical pins 71 and 72 carried, respectively, by the rails 18 and 19. Each clamp is provided with a flat portion 73, which slips over the bracket 63 or 64 into engagement with the block 61 or 62, a finger piece 74 and a flat portion 75, (Fig. 3), which swings on the pivot pin beneath the rail 18 or 19.

With this construction, when the combined ink-marking and perforating die 29 is moved from a position of pressure to a position of clearance, the stripper plate 45 rides over the upper surface of the guard plate 57, thus inserting the ink pad 56 between the marking edges 39 and the stripper plate. From an inspection of Fig. 2 it is apparent that the stripper plate studs 46 and supporting springs 49 are mounted to clear the lateral sides of the ink pad 56 and its supporting means when the die 29 is moved from the position of pressure into the position of clearance.

In order to elevate the die 29 in the position of clearance to cause the marking edges 39 to engage the ink pad 56 and be inked thereby, the inside faces of the rails 18 and 19 carry, respectively, die-elevating rails 76 and 77. Each die-elevating rail is provided with a surface 78 upon which the bottom plate 36 slides during the insertion of the ink pad 56 in between the marking edges 39 and the stripper plate and with a stop 79 against which the front face of 75

the bottom plate 36 abuts just prior to the time the die 29 moves into the position of clearance.

Each die-elevating rail is provided with a pair of inclined slots 80, (Fig. 4), extending upwardly and forwardly. These slots 80 and 81 embrace loosely, respectively, the shanks of screws 82 and 83 threaded, respectively, into blocks 84 and 85. These blocks are carried, respectively, by the bottoms of the rails 18 and 19. The screws 82 and 83 are each provided with a washer 86 interposed between the head of the screw and the adjacent die-elevating rail.

With this construction the bottom plate 36, in moving from the position of pressure to a position of clearance, slides first upon the plate 17 and then upon the surfaces 78 of the die-elevating rails. When the front face of the die bottom plate 36 engages the stops 79, the die-elevating rails are moved upwardly and forwardly, thus carrying the marking edges 38 into engagement with the ink pad 56.

Instead of an absorbent ink pad 56, the guard plate 57 may support a rubber pad 87 as indicated in Fig. 7. The rubber pad 87 may be of the type which requires to be inked in each cycle of operation of the machine. To this end, the front face of the die bottom plate 36 is provided with a pair of spaced forwardly projecting pins 89 and 90, (Fig. 5), constituting a readily removable support for a detachable inking means comprising an ink reservoir 91 and a roll 92 journaled therein.

The ink reservoir 91 is cast upon a handle 93 by means of which the die 29, or it may be, another combined ink-marking and perforating die 94, (Figs. 5 and 6), is moved from and to a position of clearance into and from a position of pressure. The die 94 has the same general construction and mode of operation as the die 29 except that the pattern perforated by its perforating tubes 95, (Fig. 5), and the pattern marked by its marking edges 96 are different from the corresponding patterns cut and marked, respectively, by the perforating tubes and marking edges of the die 29.

The handle 93 comprises a yoke, the arms of which near their rear ends are pivoted, respectively, upon screws 97, (Fig. 5), threaded into a cross-piece 98 on a block 99. The rear ends of the arms of the handle yoke are slotted to form a yoke 100, (Fig. 6) which embraces loosely the front face of the block 99. The upper arm 101, of the yoke acts as a stop to limit the upward pivotal movement of the handle 93 and the lower arm 102 acts as a stop to limit the downward pivotal movement of the handle 93.

The bottom face of the block 99 is provided with two grooves 103 and 104, (Fig. 9), which are extended within the body portion of the block laterally to the left, (Fig. 9). The block 99, with the parts carried thereby, may be secured to the pins 89 and 90 by inserting them in grooves 103 and 104, respectively, whereupon by a movement of the block 99 to the right the pins 89 and 90 are transferred into the lateral extensions of the grooves. The block 99 is locked in position on the pins by a detent 105, (Figs. 6 and 9), mounted to work through an opening in the block into the groove 104. The detent 105, (Fig. 5), is carried by the free end of a leaf spring 106 secured at its other end to the block 99.

Within this construction, when the operative pulls the handle 93 to transfer the die from the position of pressure to a position of clearance she elevates the handle about its pivotal connection

with the block 99 thus causing the roll 92 to roll over the surface of the rubber pad 87 and deposit a film of ink thereon. When the front face of the bottom plate of the die 94 strikes the stops 79 the marking edges 96 are elevated into engagement with the inked ink pad. 5

While the particulars of construction herein set forth are well-suited to various structural forms of the invention, they are not limited to these details of construction, nor to the conjoint use of all their features, nor is it to be understood that these particulars are essential since they may be modified within the skill of the artisan without departing from the true scope of the actual invention, characterizing features of which are set forth in the following claims by the intentional use of generic terms and expressions, inclusive of various modifications. 10 15

What is claimed as new is:

1. A combined ink-marking and perforating machine having, in combination, a stripper plate, a marking die having its marking edge spaced from the stripper plate, means for inking the marking edge, and means for moving the inking means and the marking edge relatively in two directions substantially normal to each other to insert the inking means between the stripper plate and the marking edge and to engage the marking edge and the inking means. 20 25

2. A combined ink-marking and perforating machine having, in combination, a stripper plate, a marking die having its marking edge spaced from the stripper plate, a stationary ink pad, and means for moving the stripper plate and the marking edge in one direction to insert the ink pad between the marking edge and the stripper plate and for moving the marking edge in another direction to cause it to engage the ink pad. 30 35

3. A combined ink-marking and perforating machine having, in combination, a stripper plate, a marking die having its marking edge spaced from the stripper plate, a stationary ink pad, means for inking the ink pad, and means for moving the stripper plate and the marking edge in one direction to insert the ink pad between the marking edge and the stripper plate and for moving the marking edge in another direction to cause it to engage the ink pad. 40 45

4. A combined ink-marking and perforating machine having, in combination, a stripper plate, a marking die having its marking edge spaced below the stripper plate, a guard plate, an ink pad carried upon the bottom face of the guard plate, a marking die having an upstanding marking edge, means for moving the stripper plate and the marking edge in one direction to insert the guard plate between the marking edge and the stripper plate and for moving the marking edge in another direction to cause it to engage the ink pad. 50 55 60

5. A combined ink-marking and perforating machine having, in combination, a guard plate, an ink pad carried upon the bottom face of the guard plate, a marking die having an upstanding marking edge, a stripper plate mounted to extend above the marking edge and spaced therefrom, means for inking the ink pad, and means for moving the stripper plate and the marking edge in one direction to insert the guard plate between the marking edge and the stripper plate and for moving the marking edge in another direction to cause it to engage the ink pad. 65 70

6. A combined ink-marking and perforating machine having, in combination, a bed, rails mounted upon the upper surface thereof, a flat 75

plate mounted upon the upper surface of the bed between the rails and secured thereto, rails mounted upon the plate, a die mounted to slide upon the plate between the rails thereof, and die-elevating rails carried by the plate rails and arranged to support the die when it is moved out of engagement with the plate.

7. In a perforating machine, the combination with a bed, rails mounted upon the upper surface 10 of the bed and projecting forward thereof, of a combined ink-marking and perforating attachment mounted upon the upper surface of the bed between the rails and secured to the forward projecting portions thereof.

8. A combined ink-marking and perforating machine having, in combination, a stripper plate, a marking die having its marking edge spaced from the stripper plate, a handle pivotally connected to the die, an ink-reservoir carried by the handle, an inking roll carried within the reservoir, means for inking the marking edge, the handle being used to move the inking roll and the die beneath the marking edge inking means and to elevate the inking roll into contact therewith and 5 cam means for causing the engagement of the marking edge and the inking means.

ARTHUR W. ALTVATER.
FRANZ WUNDER.
